(57) **CLAIM**

The ornamental design for an automobile and truck gasket-less connector, as shown and described.

DESCRIPTION

FIG. 1 is a top plan view of an automobile and truck gasket-less connector, showing my new design prior to assembly;

FIG. 2 is an elevational view of the automobile and truck gasket-less connector taken along the lines 2—2 of FIG. 1; FIG. 3 is an elevational view of the automobile and truck gasket-less connector taken along the lines 3—3 of FIG. 1; FIG. 4 is a top plan view of the automobile and truck gasket-less connector of FIG. 1 showing my new design after assembly;

FIG. 5 is a left side elevational view of the automobile and truck gasket-less connector of FIG. 4; and,

FIG. 6 is a right side elevational view of the automobile and truck gasket-less connector of FIG. 4.

1 Claim, 2 Drawing Sheets

FIG. 1.

FIG. 3.

FIG. 2.

FIG. 4.

FIG. 6.

FIG. 5.

UNITED STATES PATENT AND TRADEMARK OFFICE
CERTIFICATE OF CORRECTION

PATENT NO. : Des. 464,597 S
DATED : October 22, 2002
INVENTOR(S) : Darryl C. Bassani

Page 1 of 1

It is certified that error appears in the above-identified patent and that said Letters Patent is hereby corrected as shown below:

Title page.

Item [54], the title which reads, "**AUTOMOBILE AND TRUCK GASKET-LESS CONNECTOR**," should read -- **AUTOMOBILE AND TRUCK GASKET-LESS EXHAUST CONNECTOR.** --

Signed and Sealed this

Twenty-ninth Day of April, 2003

JAMES E. ROGAN
Director of the United States Patent and Trademark Office
